UNITED STATES PATENT OFFICE.

I. C. EMERY, OF BALTIMORE, MARYLAND, ASSIGNOR TO CHAPMAN SELF LOCKING NUT COMPANY, TRUSTEES, OF BALTIMORE, MARYLAND.

MACHINE FOR SLOTTING LOCK NUTS.

Application filed April 29, 1922. Serial No. 557,274.

To all whom it may concern:

Be it known that I, I. C. EMERY, a citizen of the United States, residing at Baltimore, in the county of Baltimore City and State 5 of Maryland, have invented certain new and useful Improvements in Machines for Slotting Lock Nuts; and I do hereby declare the following to be a full, clear, and exact description of the invention, such as will enable others skilled in the art to which it 10 pertains to make and use the same.

This invention relates to a means for making lock nuts and has for its object to provide an automatic machine which will be 15 simple in construction, certain in operation, and less costly to produce than those heretofore proposed.

With these and other objects in view, the invention consists in the novel parts and 20 combinations of parts more fully herein-after disclosed and particularly pointed out in the claims.

Referring to the accompanying drawings forming a part of this specification, in which 25 like numerals designate like parts in all the views:

Figure 1 is a side elevational view of a machine made in accordance with this invention;

Figure 2 is a view similar to Figure 1, but showing the opposite side of the machine;

Figure 3 is a view similar to Figure 1, but showing the parts in another position;

Figures 4 and 4^a constitute a plan view of 35 the parts shown in Figures 1 and 2;

Figure 5 is a side elevation of the nut made by the machine after its slit has been sawed, but before said slit has been partially closed;

Figure 6 is a view of the nut after its slit has been partially closed;

Figure 7 is a sectional view of the nuts shown in Figures 5 and 6;

Figure 8 is a detail sectional view of a 45 portion of the slit closing mechanism; and

Figure 9 is an irregular sectional view of the mechanism, taken approximately on the line 9—9 of Figure 1, looking in the direction of the arrows, certain parts being 50 shown in elevation and certain parts being omitted for the sake of clearness.

1 indicates any suitable base, from which rises a web or frame 2, having the strengthening ribs 3, and the top flanged portions 4.

55 On the supporting frame work thus pro-

vided, in suitable bearings is journalled the power shaft 6, carrying the power pulley 7 and the small gear 8, meshing with the larger gear 9 mounted on the shaft 10 carrying the saw 11, all as will be clear from 60 Figures 1, 2 and 3.

Also mounted in suitable bearings on the frame work is a second power shaft 12, carrying a second power pulley 13, and a worm 14, meshing with a worm gear 15, mounted 65 on a shaft 16, carrying a cam 17, having a cut away portion 18, as plainly shown in Figures 1 and 3.

Pivoted to the frame, as at 19, is a Y-shaped member 20, provided with the roller 70 21 adapted to ride over the surface 22 of the cam 17, and to enter said cut away portion 18, and as will be clear from the drawings, during these movements said Y-shaped member 20 will be swung on its pivot 19 from 75 the position shown in Figure 3 to that shown in Figure 1. Pivoted to the member 20, as at 23, is a second Y-shaped member 24 provided with an end 25 through which passes the adjustable rod 26, surrounded by 80 the spring 27, as illustrated. Pivoted on the shaft 30, is the bent lever 31, one end 32 of which lies in the path of the roller 33 carried by the cam 17, and the other end 34 of which is adapted to contact with the end 36 85 of the second Y-shaped member 24.

The first Y-shaped member 20 is provided near the pivot 23 with a nut holding jaw 38, and co-acting with the latter is a complementary nut holding jaw 39 carried by 90 said second Y-shaped member 24. Rising from the frame in a vertical plane near that of the saw 11, is a feed chute 40 adapted to feed nuts 41 by gravity down to the bottom 42 of said chute formed by the frame member 43 as best illustrated in Figure 9. Mounted on the worm gear 15 is a cam 45 which actuates a roller 46 carried by one end 47 of a lever 48 pivoted at 49, and whose other end 50 is attached as at 51 to the member 52, to which the stout spring 53 is joined as at 54. The other end of said spring 53 encircles the plunger member 55, which passes through the projection 56 of the frame member 43, against which said spring 53 abuts. 95

It thus happens that as the worm gear 15 revolves the cam 45 actuates the roller 46 and lever 48 to reciprocate the plunger 55 through the medium of the spring 53, and 100 110

the reciprocation of said plunger 55 pushes the bottom nuts 41 from the chute 40, into the position of the nut 56', Figure 9, which is gripped by the jaws 38 and 39, and which 5 occupies the vertical plane of the saw 11.

In the meantime, the parts are so arranged that the roller 21, has been lifted into the position shown in Figure 3, and the two jaws 38 and 39 have been swung on the 10 pivot 19 toward the right, to such an extent that the saw intersects a portion of the nut 56', and thus is the slot 57, see Figure 5, placed in said nut. As the cam 17 continues to rotate, the cut away portion 15 18 comes under the roller 21, and the Y-shaped member 20 is swung on its pivot 19 from the position shown in Figure 3 to the position shown in Figure 1, under the influence of the weight 60 which is attached 20 to the extreme end 61 of said Y-shaped member 20 by means of the cable or other connection 62, as will be readily understood.

As the slotted nut 56' returns to the position shown in Figure 1, it comes opposite the delivery chute 63, and falls by gravity down said chute until it strikes the arm 64, which intersects said chute. Said arm 64 is rigid with the bent lever 65 pivoted 30 at 66, and provided with the angular portion 67, provided with the weighted end 68 to which is attached the yoke 69. To the yoke 69 is secured one end of the flat steel band 70, which passes over the hub 71 of 35 the cam 17, and has its other end secured to the yoke 72 which is attached to the extreme end, as at 73 to the Y-shaped member 20, as illustrated.

It thus results that as said Y-shaped member 20 is moved from the position shown 40 in Figure 1 to the position shown in Figure 3 said flat steel band 70 is straightened out, and the lever 65 is swung on its pivot 66, to the end that its bent portion 64 is 45 retracted from the said chute 63. But while the extreme corner 74 of the bent portion 64 is passing out of said chute 63, said corner serves to lift the slotted nut 56' from the dotted line position illustrated in 50 Figure 3, until the center of said nut occupies a position above the center 75 of a compressing mechanism to be described.

It should be stated, however, that the chute 63 is cut away in order to permit 55 the corner 74 of said member 64 to lift the nut into said last mentioned position, all as will be clear from Figures 1 and 8. Just as the slotted nut 56' is brought into the position illustrated in Figure 8, the parts 60 are so timed that the bending of the parts 77 of the nut 56' toward the part 78 of said nut (see Figure 6) will take place in the manner now to be disclosed.

That is, there is mounted in that portion 65 of the framework 80, see Figure 9, the screw

threaded end 81, of a compression member 82, which has keyed thereto as at 83 one end of an oscillating member 84, see Figure 1. The other end of said oscillating member 84 is pivoted at 85 to the member 70 75 86, through which slides the member 87, pivoted at 88 to the member 89, which is pivoted at 90 to the cam 17, all as will be clear from Figures 1 and 9. The members 86 and 89 are surrounded by the coil spring 91, and as the cam 17 rotates it is evident that the parts are so proportioned and disposed that the said member 84 will oscillate to and fro around the point 75 as a center, with the result that the compressing member 82 will be moved first toward the right, as seen in Figure 9 and then toward the left, due to the action of its screw threaded portion 81 in the frame member 80, which acts as a nut for said screw threaded portion 81. Opposite to the said reciprocating compressing member 82 is the adjustable stationary compressing member 92, and it is evident that the portion 77 of the nut 56' will be bent 90 from its position parallel to the member 78, as seen in Figure 5, to its position inclined to said portion 78, as illustrated in Figure 6. The parts are so timed that as this compressing action is completed, the edge 74 of the bent portion 64 will have left the nut so that the said nut will fall back under the action of gravity into the delivery chute 63, and will traverse said chute until its extreme end 95 has been reached, and thus will be carried away from the other mechanism into any suitable receptacle not shown.

The operation of this mechanism will be clear from the foregoing, but may be briefly summarized as follows:

Unslotted nuts 41 are placed in the chute 40, with the lower nut resting on the bottom 42 of said chute, as seen in Figure 9. Power is imparted through the pulley 13 to the power shaft 12, which operates the worm gear 15, and cam 17. The rotation of the cam 17 moves the end 61 of the Y-shaped member 20, up and down, through the medium of the roller 21 and thus oscillates 110 said Y-shaped member around the pivot 19 as a center. Said Y-shaped member has pivoted thereto as at 23 the Y-shaped member 24, which carries a holding jaw 39, which latter co-acts with the holding jaw 38 of the member 20, and thus do the two jaws grip a nut 56 between them. The spring 27 associated with the member 24 governs the gripping power of the jaws 38 and 39, and said jaws being in the plane 115 of the saw 11, when they oscillated around the pivot 19 they carry the nut 56 across the cutting edge of the saw 11, and thus is a slit 57 placed in the nut. In order that the saw may reach beyond the center of the 120 125 130

nuts, said jaws 38 and 39 are provided with a slit or slot 100, see Figure 9. The saw 11 is operated by the following means:

Power is imparted to the pulley 7, and shaft 6, whereupon the small gear 8 turns the large gear 9 and shaft 10 on which the saw is mounted. The unslotted nuts 41 are moved from their position shown in Figure 9 to the position of the slotted nuts 56 as follows:

The worm gear 15 carries a cam 45 which actuates the lever 48 through the medium of the roller 46, and said lever through its connection 51 moves the plunger 55 toward the left, as seen in Figure 9. This movement of the plunger 55 forces an unslotted nut 41 from its position shown in Figures 4 and 9 to the position of the slotted nut 56', but not over the delivery chute 63. When in the position 56, jaws 38 and 39 are separated by reason of the fact that the roller 33 has operated the lever 31 to cause its end 34 to act upon the projection 36 of the member 24, and thus to raise the jaw 39 away from the jaw 38. After said roller 33 has passed the end 32 of the lever 31 however, the spring 27 will swing the jaw 39 around its pivot 23 and thus will said jaw 39 close down upon the nut held by the jaw 38, and a continued rotation of the cam 17 will swing the member 20 including the jaws 38 and 39, as well as the nut 56', across the edge of the saw 11, all as above disclosed.

On the other hand, when the cam 17 reaches such a position that the roller 21 again occupies the cut away portion 18, the jaws 38 and 39 will occupy such a position as to cause the nut 56' to be in line with, but to one side of the delivery chute 63. Now, when the roller 33, through the medium of the lever 31 and its end 34, again lifts said jaw 39 to release its nut, the plunger 55 will again act to push another nut 41 from the bottom 42 of the chute into a position between said jaws, and this third nut will push the second nut out from the position between said jaws toward the left, as seen in Figure 9, and this said second nut will push toward the left the first nut 56', not shown in Figure 9, but illustrated in Figure 4, and this said first nut will fall into the mouth of the delivery chute, when it is pushed again by the plunger 55. In other words, there are always three nuts in line as seen in Figure 4, ready to be operated upon by the plunger 55.

The spring 53 serves a double function. It serves to cushion the action of the parts should they become jammed and thus prevent the breaking of the machine, and it also serves to return the plunger 55 after it has pushed a nut into the position between the jaws.

It sometimes happens that nuts of different sizes need to be slotted and also it some-

times happens that the depth of the slots 57 need to be varied. In order to make this machine accommodate itself to these various requirements, the shafts 6 and 10, Figure 1, are mounted upon a member 102, which is 70 slidably connected with that portion of the frame 4 which supports it. That is, said member 102 is provided with the spline 103 which fits into the framework and with the aid of the fastenings 104 holds the parts 75 firmly in position. On the other hand, when the saw 11 is to be adjusted toward or from the jaws 38 and 39, the fastenings 104 are loosened, and the shafts 6 and 10 together with their co-acting parts, are all moved 80 relative to the framework 4 by means of the adjusting screw 105, to the end that slots of different depths and nuts of different sizes may be acted upon.

It will thus be seen that the Y-shaped members 20 and 24 provide the gripping jaws 38 and 39 to grip the nuts to be slotted, that the plunger mechanism 55 and its associated parts provide means to feed the nuts to the jaws 38 and 39, that the cam 90 17 and its associated parts provide means to move the gripped nuts across the path of the saw 11, or other equivalent slotting means; that the screw threaded member 82 and its associated parts provide means to 95 permanently bend the part 77 of the slotted nut toward the part 78 thereof, to the end that the screw threads in the part 77 are displaced relative to the screw threads in the parts 78 and that therefore when a 100 slotted nut such as 56' is placed on a bolt the threads of the bolt will tend to move the part 77 of the slotted nut back into its position parallel to the part 78, as is illustrated in Figure 5. This tendency on 105 the part of the screw threads of the bolt will be resisted by the natural spring tension of the metal, and therefore will the part 77 bind tightly against the threads of the bolt and thus tend to lock the nut 110 in place.

It is obvious that those skilled in the art may vary the details of construction as well as the arrangement of parts without departing from the spirit of the invention, and therefore I do not wish to be limited to the above disclosure except as may be required by the claims.

What is claimed is:

1. In a lock nut slotting machine, the combination of a member directly pivoted to the frame of said machine and provided with a gripping jaw; another member provided with a gripping jaw pivoted to said first named member; means to cause said jaws to grip a nut to be slotted; and means to slot the gripped nut. 120

2. In a lock nut slotting machine, the combination of a member directly pivoted to the frame of said machine and pro- 130

vided with a gripping jaw; another member provided with a gripping jaw pivoted to said first named member; reciprocating means to feed a nut to said jaws; means 5 to cause said jaws to grip the fed nut; and means to slot the gripped nut.

3. In a lock nut slotting machine the combination of a cutter; a pivoted member provided with a gripping jaw; another 10 member provided with a gripping jaw pivoted to said first named member; automatic reciprocating means to feed a nut to said jaws; means to cause said jaws to grip the fed nut; and means comprising 15 a rotating cam to move the gripped nut toward said cutter.

4. In a lock nut slotting machine the combination of a cutter; means to grip the nut to be slotted; means to feed said nut 20 to said gripping means; means to cause the gripped nut to cross the cutting edge of said cutter; means to release the slotted nut from said gripping means; means to deform the slot produced; and means to position the slotted nut with respect to said 25 deforming means.

5. In a lock nut slotting machine the combination of a cutter; means to grip the nut to be slotted; means to feed said nut 30 to said gripping means; means to cause the gripped nut to cross the cutting edge of said cutter; means comprising a lever to release the slotted nut from said gripping means; means to deform the slot produced; and means to position the slotted nut with respect to said 35 deforming means.

6. In a lock nut slotting machine the combination of a cutter; means to grip the nut to be slotted; means to feed said nut to said 40 gripping means; means to cause the gripped nut to cross the cutting edge of said cutter; a roller carried by said last named means; means comprising a lever actuated by said roller to release the slotted nut from said 45 gripping means; means to deform the slot produced; and means to position the slotted nut with respect to said deforming means.

7. In a lock nut slotting machine the combination of a cutter; means to grip the nut 50 to be slotted; means to feed said nut to said gripping means; means to cause the gripped nut to cross the cutting edge of said cutter; means to release the slotted nut from said gripping means; means to deform the slot produced; means comprising a lever to position the slotted nut with respect to said 55 deforming means; and means associated with said gripping means to actuate said positioning means.

8. In a nut slotting machine the combination of a slot cutter; a pair of holding jaws to grip the nut to be slotted; a pivoted member carrying one of said jaws; a plunger to feed the nut to said jaws; means to feed 60 the nut to said plunger; and means to cause

said pivoted member to move the gripped nut across the slotting edge of said cutter, substantially as described.

9. In a nut slotting machine the combination of a saw; a pair of gripping jaws; a plunger; means to feed nuts in succession to said plunger; means to cause said plunger to successively feed nuts to said jaws; means to successively cause said jaws to grip the fed nuts; means to successively cause said 75 jaws to move the gripped nuts across the cutting edge of said saw and to retract said nuts after the slotting operation; and means to cause said jaws to release the retracted nuts, substantially as described. 80

10. In a nut slotting machine, the combination of a cutter; means to grip the nut to be slotted; means to cause said gripping means to subject said nut to the slotting action of said cutter; and means to bend one 85 portion of the slotted nut toward the other, substantially as described.

11. In a nut slotting machine the combination of a slot cutter; a movable jaw to grip the nut to be slotted; means to feed 90 said nut to said jaw; means to cause the gripped nut to cross the cutting edge of said cutter; and means to permanently bend one portion of the slotted nut toward the other, substantially as described. 95

12. In a nut slotting machine, the combination of a slot cutter; a pair of holding jaws to grip the nut to be slotted; a pivoted member carrying one of said jaws; means to cause said pivoted member to move the 100 gripped nut across the slotting edge of said cutter; and means to permanently deform said nut by bending one threaded portion toward the other, substantially as described.

13. In a nut slotting machine the combination of a saw; a pair of gripping jaws; a plunger; means to feed nuts in succession to said plunger; means to cause said plunger to successively feed nuts to said jaws; means to successively cause said jaws to grip the 105 fed nuts; means to successively cause said jaws to move the gripped nuts across the cutting edge of said saw and to retract said nuts after the slotting operation; means to cause said jaws to release the retracted nuts; 110 and means to permanently deflect one portion of the slotted nut toward the other, substantially as described. 115

14. In a nut slotting machine the combination of a saw to slot the nuts; a pair 120 of gripping jaws; a plunger for feeding the nuts to said jaws; a cam for causing the jaws to subject the nuts to the slotting action of said saw; means associated with said cam for causing said jaws to release the nuts after the slotting action is completed; means for permanently deflecting one portion of the slotted nut toward the other; and means associated with said cam for actuating said 125 deflecting means, substantially as described. 130

15. In a nut slotting machine the combination of a saw to slot the nuts; means comprising a power shaft and gears for operating said saw; a pair of gripping jaws; a plunger for feeding the nuts to said jaws; a cam for causing the jaws to subject the nuts to the slotting action of said saw; means comprising a worm and worm gear for operating said cam; means comprising a pivoted member associated with said cam for causing said jaws to release the nuts after the slotting action is completed; means for permanently deflecting one portion of the slotted nut toward the other; and means associated with said cam for actuating said deflecting means, substantially as described.
16. In a nut slotting machine the combination of a saw to slot the nuts; a pair of gripping jaws; a plunger for feeding the nuts to said jaws; a cam for causing the jaws to subject the nuts to the slotting action of said saw; means associated with said cam for causing said jaws to release the nuts after the slotting action is completed; means comprising an oscillating screw threaded member for permanently deflecting one portion of the slotted nut toward the other; and means comprising an oscillating lever like member rigid with said screw threaded member and associated with said cam for actuating said deflecting means, substantially as described.
17. In a nut slotting machine the combination of means to grip the nuts; means to feed the nuts to the gripping means; means to move the gripped nuts to the slotting means; and means to permanently deform the slot produced, substantially as described.
18. In a lock nut slotting machine the combinations of means to provide a nut with a slot; a movable slot deforming means; means to feed said slotted nut to said slot deforming means; and movable means to position the center of the fed nut out of the line of movement of said slot deforming means.
19. In a lock nut slotting machine the combinations of means comprising pivoted grippers and a cutter to form a slot in a nut; a movable slot deforming means comprising a screw actuated compressing member; means to feed said slotted nut to said slot deforming means; and movable means to position the center of the fed nut out of the line of movement of said slot deforming means.
20. In a lock nut slotting machine the combinations of means comprising pivoted grippers and a cutter to form a slot in a nut; a movable slot deforming means comprising a screw actuated compressing member; means to feed said slotted nut to said slot deforming means; movable means comprising a pivoted lever to position the center of the fed nut out of the line of movement of said slot deforming means; and connections between said grippers and said lever to actuate the latter.

In testimony whereof I affix my signature.

I. C. EMERY.
